Juliana Agon**[57] CLAIM**

The ornamental design for a control head for a mobile radio, as shown and described.

DESCRIPTION

FIG. 1 is a top, front and right side perspective view of a control head for a mobile radio showing my new design;

FIG. 2 is a top plan view thereof;

FIG. 3 is a front elevational view thereof;

FIG. 4 is a left side elevational view thereof;

FIG. 5 is a right side elevational view thereof;

FIG. 6 is a bottom plan view thereof;

FIG. 7 is a rear elevational view thereof;

FIG. 8 is a top, front and right side perspective view of a second embodiment of the control head illustrated in FIG. 1;

FIG. 9 is a top plan view thereof; and,

FIG. 10 is a front elevational view thereof.

The views of the second embodiment not shown are the same as the corresponding views of the first embodiment.

FIG. 1

FIG. 2

FIG. 3

FIG. 4

FIG. 5

FIG. 6

FIG. 7

FIG. 8

FIG. 9

FIG. 10
